Specification for Design.

Patented July 11, 1922.

Application filed February 23, 1921. Serial No. 447,317. Term of patent 3½ years.

To all whom it may concern:

Be it known that I, FRANK MEYER, a citizen of the United States, and a resident of Lakewood, Ohio, have invented a certain new, original, and ornamental Design for Safety Paper, of which the following is a specification, reference being had to the accompanying drawing.

The accompanying drawing illustrates the design applied to a portion of safety paper.

I claim as my invention:

The ornamental design for safety paper, as shown.

FRANK MEYER.
